UNITED STATES PATENT OFFICE.

GEORGE A. MYERS, OF SCHOOLCRAFT, MICHIGAN, ASSIGNOR OF ONE-HALF
TO JESSE P. EARL, OF SAME PLACE.

MOTOR.

SPECIFICATION forming part of Letters Patent No. 328,964, dated October 27, 1885.

Application filed June 2, 1884. Serial No. 133,588. (No model.)

To all whom it may concern:

Be it known that I, GEORGE A. MYERS, a citizen of the United States, residing at Schoolcraft, in the county of Kalamazoo and State of Michigan, have invented certain new and useful Improvements in Motors for Churns, Washing-Machines, &c., of which the following is a specification, reference being had therein to the accompanying drawings.

10 The invention relates to mechanism for reciprocating the dasher-rods of churning, washing-machines, or any such class of machines of which a reciprocating rod forms an actuating part; and it consists, mainly, in attaching such a rod to a vertical head-block which is reciprocated by a parallel motion, both rods of the parallel motion being pivoted to the upright arm of a fixed bracket, and the lower arm of the same being vibrated by a crank-shaft having bearings in the frame of the machine.

15 It further consists in certain mechanism for rotating the churn or washing-machine while the rods are reciprocating, which mechanism is herein more fully described, and pointed out in the claims.

20 In the drawings accompanying and forming part of this specification, Figure 1 represents a side elevation of the machine with the side 30 of the tub or churn broken away to show the dashers or pounders. Figs. 2 and 3 show a part of the mechanism for rotating the tub or churn, and Fig. 4 is a detail view of the crank-shaft.

25 In the accompanying drawings, A represents the frame-work of the machine, composed of the rectangular horizontal frame *a* and the rectangular upright frame *a'*, fixed to the front end of the former.

30 *B* is a crank-shaft having transverse bearings in the upper part of the frame *a'*, and provided with the two equal and similar cranks *b* and *b'*, situated at equal distances on each side of the center of the crank-shaft and having opposite directions, so that when one is up the other is down. *b* is a fly-wheel provided on its rim with a proper handle, which wheel is fixed to the end of the crank-shaft that extends outside of the frame *a'* on the side 45 of the crank *b*; and *b'* is a pin extending at

right angles from the crank-shaft, between the fly-wheel and the frame *a'*, for a purpose hereinafter explained.

55 *C* and *C'* are two similar and equal brackets extending rearward from the side beams of the frame *a'*. The bracket *C* is attached to upright frame *a'* at a proper distance below the crank-shaft, and the bracket *C'* is attached to upright frame *a'* at a proper distance above the crank-shaft, and they have respectively 60 the upturned similar vertical extensions *c* and *c'*.

65 *D* is a head-block properly formed to carry a dasher or pounder rod on its vertical face, so that said rod may be longitudinally adjustable on the same, and having its upper end pivoted to the rear end of a link, *d*, which pivots by its front end to the upper end of the extension *c*; and *d'* is an actuating-lever pivoted by its rear end to the lower end of the 70 head-block *D* and connecting the same with the crank *b*. The lever *d'* connects by its front end with the crank *b* by means of the longitudinal slot *d''*, and pivots on the extension as far below the pivot-point on the same of the 75 link *d* as their rear ends pivoted on the head-block *D* are apart.

80 *d''* is that part of the lever *d'* lying between the extension *c* and the head-block *D*, and equals in length the link *d*, consequently forming, with the latter and the said head-block and extension, a parallel motion, which, as the extension is vertical, will reciprocate the head-block and attached rod vertically by the vibration of the lever *d'*.

85 *E* is a head-block similar to *D*, or of any other proper form, and *e* is a link similar to the link *d*, joining the upper end of said block to the upper end of the extension *c'* in a similar manner.

90 *e'* is a lever, the rear part, *e''*, of which forms with said link a parallel motion, in all respects similar to that above mentioned, by pivoting on the extension *c'* and lower end of block *E*. The front end of the lever *e'* is provided with the holes *e''* at proper distances apart, into any one of which the upper end of a pitman, *e''*, pivots, the lower end of the same being properly connected to and reciprocated by the crank *b'*.

F F' are rods of churn-dashers, washing-machines, or any machine of which they might form an actuating part. The said rods are attached to and vertically adjustable on the blocks D and E, respectively, either by slots and screws, proper openings in the head-blocks, or other suitable means, and carry at their lower ends dashers, pounders, or similar devices.

10 G is a horizontal ratchet-wheel pivoted centrally to a cross-beam of the frame a, near the rear end of the latter, and having its under surface turning on the friction wheels or rollers g g, which have proper bearings in the frame a.

15 g' g' are similar lugs fixed equidistantly around the rim of the upper surface of said wheel.

H is a vertical lever provided toward its upper end with the holes h h, at proper distances apart, by any one of which holes the lever may be pivoted to the outer surface of the side beam of the frame a', vertically below the crank-shaft and pin b'.

h' is a piece of metal secured vertically to 25 the upper end of said lever, and provided with the longitudinal slot h'. The said slot is so formed that the pin b', which passes through it, does not bear against its ends as the crank-shaft turns, but does bear on its sides, and 30 thus reciprocates the upper end of the lever H, the lower end of the same being reciprocated in the opposite direction.

I is a horizontal rod pivoted loosely to the lower end of the lever H, lying upon proper 35 guiding-supports i, attached to the frame a, and having its rear end formed into a pawl, i', which engages and pulls to the front the meeting edge of the ratchet-wheel when the lower end of the lever H moves forward.

40 J is a tub, churn, or similar device, with its bottom resting on the lugs g' g', and secured centrally to the ratchet-wheel by screws through said bottom, or by means of uprights fixed to the ratchet-wheel, which have proper devices 45 to clutch its top or edge.

The ratchet-wheel, rod I, lever H, attached slotted piece h', and the pin b' on the crank-shaft are so constructed and arranged as to 50 revolve the ratchet-wheel the distance of one tooth when the dasher or pounders do not engage the material or substance in the tub or churn.

55 It is evident from the description that when the fly-wheel is turned the rotation of the crank-shaft will vibrate the levers d' and e', which, by means of the parallel motions of which their rear ends form part, one reciprocating the head-blocks D and E, and attached rods, respectively, and as the cranks b and b'

are set oppositely the said rods will be reciprocated alternately.

The mechanism for rotating the tub or churn is so arranged that it begins to act just as one dasher has reached its lowest point, the other being at its highest point, so that it 65 acts when both are disengaged, which is an important feature.

When it is desired to shorten the stroke of the rod attached to the head-block E, the end of the pitman e' is engaged in one of the 70 holes e', near to the pivot of the lever e' on the extension c', and the reverse is done to lengthen the stroke.

The rod I can be made to carry the ratchet-wheel more than the distance of one tooth by 75 pivoting the lever H, by one of the holes h, nearer to its upper end.

Having thus described my invention, what I claim as new, and desire to secure by Letters Patent, is—

1. In a machine for reciprocating dasher or pounder rods, the combination, with the frame A, bracket C, provided with the extension c, and crank-shaft B, turned by any proper means, of the lever d', provided with slot d', 85 engaging the crank of said shaft, link d, and head-block D, properly formed to carry vertically upon it a longitudinally-adjustable rod, F, substantially as specified.

2. In a machine to reciprocate dasher or 90 pounder rods, the combination, with the frame A, bracket C', provided with the extension c', and crank-shaft B, turned by any proper means, of the pitman e', connected to the crank of said shaft, lever e', provided with the holes e' e', link e, and head-block E, properly formed to carry vertically upon it a longitudinally-adjustable rod, F', substantially as specified.

3. In a machine to reciprocate dasher or 100 pounder rods, the combination, with the frame A, having attached the brackets C and C', crank-shaft B, turned by any proper means, and provided with the pin b', levers d' and e', links d and e, pitman e', and head-blocks D and E, of the lever H, provided with holes h 105 h and slotted piece h', rod I, provided with pawl i', and ratchet-wheel G, pivoted centrally at a proper point on the frame A and turning in the friction-wheels g g, all constructed and arranged as shown and described, for the purposes specified.

In testimony whereof I affix my signature in presence of two witnesses.

GEORGE A. MYERS.
